UNITED STATES PATENT OFFICE

124,727

DESIGN FOR A PACKAGE WRAPPER

Max G. Soltz, New York, N. Y., assignor to Traver Corporation, Chicago, Ill., a corporation of Illinois

Application September 7, 1940, Serial No. 94,876

Term of patent 14 years

To all whom it may concern:

Be it known that I, Max G. Soltz, a citizen of the United States, residing at New York city, in the county of New York and State of New York, have invented a new, original, and ornamental Design for a Package Wrapper, of which the following is a specification, reference being had to the accompanying drawings, forming a part thereof.

In the drawings:

Figure 1 is a front elevational view of the closed package formed from the wrapper;

Figure 2 is a side elevational view thereof;

Figure 3 is a rear elevational view thereof;

Figure 4 is a side elevational view of the closed side thereof;

Figure 5 is an end elevational view thereof;

Figure 6 is an inside plan view of the package wrapper in folded position; and

Figure 7 is a plan view of the package wrapper in unfolded position.

I claim:

The ornamental design for a package wrapper, as shown and described.

MAX G. SOLTZ.
